[57] CLAIM

The ornamental design for tool display rack, as shown and described.

DESCRIPTION

FIG. 1 is a perspective view of a tool display rack showing my new design;

FIG. 2 is a left side elevational view thereof;

FIG. 3 is a rear elevational view thereof;

FIG. 4 is a top view thereof;

FIG. 5 is a front elevational view thereof; and,

FIG. 6 is a bottom plan view thereof.

The broken line disclosure of tools in FIG. 1 is for illustrative purpose only.
